UNITED STATES PATENT OFFICE.

HARRY SWINGLEHURST, OF COLLINGSWOOD, NEW JERSEY, ASSIGNOR TO SCOTT & WILLIAMS, INC., OF BOSTON, MASSACHUSETTS, A CORPORATION OF NEW JERSEY.

DIAL-POSITIONING MECHANISM FOR RIB-KNITTING MACHINES.

1,056,133.

Specification of Letters Patent.

Patented Mar. 18, 1913.

Application filed October 31, 1912. Serial No. 728,918.

To all whom it may concern:

Be it known that I, HARRY SWINGLEHURST, a citizen of the United States, residing at Collingswood, in the county of 5 Camden and State of New Jersey, have invented a certain new and useful Improvement in Dial-Positioning Mechanism for Rib-Knitting Machines, of which the following is a specification.

10 My invention relates to circular rib knitting machines of the cylinder and dial type and consists of new and improved means for maintaining the lateral position of the needle dial with respect to the needle cylinder.

15 In the accompanying drawings, Figure 1 is a section of a rib knitting machine equipped with my device; Fig. 2 is an under plan of the needle dial shown in Fig. 1; Fig. 20 3 is a section on the line III—III showing the end of the roller-carrying lever.

In well-known machines of this type the longitudinally grooved needle cylinder or carrier, 1, which, without departing from 25 my invention, may be either fixedly attached to the bed-plate A, or be free to rotate thereon, is centrally mounted with respect to the internal shaft or stem 2, which serves to support the needle dial 3. In case the 30 machine is of the type illustrated in the drawings in which the needle cylinder is stationary, it is necessary to provide means for holding the needle dial stationary with respect to said cylinder and the rotating stem 35 2. In case the needle cylinder rotates it is also necessary to rotate the needle dial. The particular devices about to be described may be employed without change in either 40 situation, although I have chosen to illustrate them in connection with a fixed-cylinder machine.

Mounted to rotate upon the bed plate A is the usual cam cylinder 4. This cam cylinder by the usual means (not shown) is employed to drive the dial cam cap 5, which rotates with the stem or shaft 2, being held against gravity by its bearing upon the upper surface of the needle dial 3. Ordinarily 45 the central stem rotates with the cylinder cam carrier, by whatever well-known means may be employed, and it follows that the cam cap 5 may be fixed upon the stem except in a vertical sense and that the needle dial 3 must be free to rotate with respect to 50 said stem. At the bottom of the stem a

grooved collar 6 and oil cup 7 are suitably and fixedly mounted.

The usual prior art arrangement for maintaining the dial in a fixed relation to the cylinder comprises inter-meshing polished lugs, or dogs, one upon each of said members, between which dogs the fabric passes as it is withdrawn by the take-up mechanism beneath the machine.

The considerable strain resulting from the 35 reaction of the dial needles with their cams is necessarily transmitted through the fabric between the pairs of dogs, and I am aware of certain attempts in the prior art to minimize the friction created upon the fabric, 70 which has a tendency to leave a mark caused by distorted stitches at the region acted upon by the dogs. One device of this character comprises the provision of anti-friction wheels to replace the dogs carried respectively by the cylinder and dial. While this device is effective to decrease the strain upon the fabric and to reduce the marking thereof to a minimum, I have found that the necessarily small diameter of the wheels employed contributes to a grave defect in the operation of the machine, especially when starting it up with the needles bare. Under these circumstances, or when there is a 75 broken needle, holes in the fabric are liable to occur, and, as heretofore made, the anti-friction wheel or roller being unprotected with respect to the fabric, was liable to penetrate a large hole, allowing portions of the fabric to jam between the wheel and its 80 bearing, to thereby cause locking of the wheel on its shaft, and sometimes to cause the deflection of the dial, even to an extent resulting in the breakage of all of the needles in engagement with each other. I obviate these difficulties by mounting the anti-friction roll 10 in a cell or pocket on a lever 11 occupying a substantially radial position on the under side of the needle dial 3, and in engagement with the usual fixed but removable polished lug 12 on the inner surface of the needle cylinder. The roller 10, which may be formed as a cylindrical casting providing a channel for anti-friction 85 balls 13, is mounted on a screw or stud 14 90 taking into a depending lug 15 at the outer end of said lever.

As shown in Fig. 3 the roller 10 is housed in a concentric cell or hollow 16 in the end 105 of the lever, the wall of which cell is cut 110

away vertically on one side of and beneath said roller. The outer end of the lever 11 in the neighborhood of the flange 17 which forms the remaining wall of the concentric hollow 16 presents rounded and smoothed surfaces. The outer end of the flange 17 is substantially flush with the face of the wheel 10. It will be apparent that the flange 17 acts as a guide for defective fabric, to prevent the entrance of any part of the fabric, whether the raw edge of a large hole, or a floating thread or mass of threads, between the wheel and its bearing stud or screw 14, while exposing a part of the wheel tangent to a vertical plane for contact with the fabric moving on the face of the lug 12. This structure thus enables the safe passage of such defective fabric without preventing the useful function of the wheel.

20 The lever 11 is adjustable against the tension of spring 21, about its central pivot 18, by means of the thumb screw 19, threaded into a stud 20 on the under side of the dial 3 to slightly vary the adjustment of the dial 25 needles with respect to the cylinder needles, for instance to compensate for the altered position of the dial due to a change in the thickness of the fabric between the dogs 10 and 12.

30 It will be noticed that the flange 17 extends above the roller 10 throughout an arc of substantially 120° on the upper side of said roller and for some distance beyond the end of said arc on the side of the roller 35 which is not in contact with the fixed dog 12.

What I claim is:

1. In a circular knitting machine, a needle cylinder, a needle dial, a lug or dog upon the inner surface of the needle cylinder, an

anti-friction wheel carried by the dial, and a fabric shield or guard extending over that part of the periphery of said wheel which is nearest the needle dial.

2. In an anti-friction dog for rib knitting machines, a wheel, a stud upon which said wheel is mounted and means to hold the stud comprising a structure having a concentric cell or pocket formed therein to receive said wheel, and an opening into said pocket to expose a part only of the periphery of the wheel.

3. In an anti-friction dial positioning device for circular rib knitting machines, needle carriers, a lever, means to support said lever on one of said carriers, a recess in the end of said lever forming a flange at the end of said lever on that side approached by the forming fabric, an anti-friction wheel mounted to rotate within said recess, and a coöperating dog to position the fabric in contact with an exposed part of said wheel.

4. In a rib knitting machine, a cylinder, a dial, a lever mounted on the dial, a stud on said lever having its axis substantially radial with respect to the axis of rotation of the machine, a wheel mounted to rotate about said stud, a fabric guard for said wheel, and an abutment on the needle-cylinder to support the fabric in contact with the periphery of said wheel.

In testimony whereof, I have signed my name to this specification, in the presence of two subscribing witnesses.

HARRY SWINGLEHURST.
